UNITED STATES PATENT OFFICE.

LEO A. MUNDWILLER AND HERBERT A. NOEDEL, OF BERGER, MISSOURI.

RAIL-BRACE.

1,168,954.

Specification of Letters Patent. Patented Jan. 18, 1916.

Application filed September 16, 1915. Serial No. 50,995.

To all whom it may concern:

Be it known that we, LEO A. MUNDWILLER and HERBERT A. NOEDEL, citizens of the United States, residing at Berger, in the 5 county of Franklin, State of Missouri, have invented a new and useful Rail-Brace; and we do hereby declare the following to be a full, clear, and exact description of the invention, such as will enable others skilled in 10 the art to which it appertains to make and use the same.

This invention relates to an improved adjustable rail brace, and an object of the invention is to provide a brace for not only 15 preventing the rails from spreading, but to prevent the upper portions of the rails or treads from leaning or bending outwardly.

Another object of the invention is to provide a device comprising certain new and 20 improved features of construction.

One of the features of construction is the provision of a rail brace consisting of two sections having adjustable connections, the outer end portion of each section having 25 reinforcing or bracing means suitably welded into shape to brace and hold the treads of the rails rigidly and firmly against leaning or bending outwardly. In other words, the tighter the sections are drawn 30 together, the tighter the bracing means will wedge against the web and the under portion of the tread.

In practical fields the details of construction may necessitate alterations falling 35 within the scope of what is claimed.

The invention comprises further features and combinations of parts hereinafter set forth, shown in the drawings and claimed.

In the drawings—Figure 1 is a transverse 40 sectional view through a pair of rails mounted upon a tie, and illustrating the rail bracing means or anti-spreading means in full lines as applied to the rails. Fig. 2 is a plan view of Fig. 1. Fig. 3 is a detail perspective 45 view of one end of one of the sections of the rail brace, showing the bracing means for reinforcing the rail. Fig. 4 is a sectional view through one of the bracing means at the outer end of one of the sections.

50 Referring to the drawings, 1 and 2 designate two rails, and 3 the tie on which the rails are secured by the spikes 4.

The rail brace consists of the two sections 5 and 6, which are substantially flat, as 55 shown. However, the adjacent ends of the sections are provided with cylindrical

threaded extensions 7 and 8, which are connected by a turn buckle 9, so that by turning the buckle and owing to the threads of the cylindrical extensions being right and left, the sections 5 and 6 will be drawn axially toward each other. Also threaded upon the extensions 7 and 8 are lock nuts 10 and 11, which are designed to be turned home against the end of the turn buckle 9, thereby preventing the same from unscrewing. In constructing the sections 5 and 6, the outer end of each section is bent upon itself, as shown at 12, after which the bent portion 13 is welded in any suitable manner 60 against the end part of the section. Rising upwardly and extending toward the outer face of each rail and from the bent part 13 is a bracing and wedging member 14. This member in cross section upon either of the 65 lines 4—4 or 5—5 is T-shaped, as shown, thereby affording a firm brace, one that will not become distorted, bent or irregular. In constructing this bracing or wedging member, its extreme lower base portion 15 is 70 welded to the bent portion or part 13 securely and firmly. The base portion 16 extends slightly angularly upwardly and toward the outer face of the web of each rail, from the base portion 15, and is spaced 75 against the upper face of the section (which extends under the base of the rail) to form a space 17 between the upper face of the section and the base 16, into which space 17 the outer part of the base of the rail wedges, 80 that is, when the section is drawn toward the rail. The upwardly extending part 18 of the bracing or wedging member extends 85 upwardly and toward the web of the rail and at an acute angle to the outer face of the web and at an obtuse angle to the base portion 16, so that in case the web tends to lean outwardly, outward and downward pressure will be exerted upon the part 18, 90 forcing the part 16 toward and firmly 95 against the outer portion of the base of the rail. The part 18 terminates at its upper end in a portion 19 which is in parallelism 100 with the web of the rail, and which terminates short of the under part of the outer 105 portion of the tread of the rail.

The web 20 of the wedging or bracing means or member of the shape shown is molded or otherwise constructed or welded integral with the parts 15, 16, 18 and 19, in 110 order to afford a rigid structure, or wedge between the under face of the tread and the

upper face of the base of the rail. The web 20 is cut-away or cut-out, as shown at 21, and welded integrally into this cut-out or cut-away portion is the angular part 22 of the reinforcing supporting plate 23, the parts 24 and 25 of which firmly and rigidly engage the under face of the outer part of the tread and the outer face of the web of the rail, thereby forming a suitable abutment means for the rail, to prevent outward leaning or bending of the rail, incident to the wheels of the rolling stock traveling upon the rails. The part 25 of the plate 23 is first riveted, as shown at 27, to the portion 19 of the web, after which the parts 24 and 25 are firmly welded or otherwise integrally connected to the inner face and the upper edge of the part 19, thereby providing an improved, firm and rigid wedging or bracing member for the rail, which will firmly or rigidly support the rail and resist the leaning or bending of the rail incident to all lateral strain as the wheels of the rolling stock pass over the rails. In case there is any tendency for the outer portion of the tread of the rail to bend or be beaten downwardly by the constant travel of the wheels on the rails, the wedging or bracing member will be forced toward the base of the rail, and the tighter the turn buckle is screwed, the bracing or wedging member will force toward the web of the rail and upwardly against the under face of the tread, thereby insuring efficient and practical bracing means for the rail.

The invention having been fully set forth, what is claimed as new and useful is:—

1. Bracing means for a pair of rails consisting of two sections extending under the bases of both rails and having their inner adjacent ends adjustably connected and axially alined; the outer end portion of each section beyond where it passes under the base of a rail being bent upon itself, the bent portion being welded integrally to the upper face of the section, a wedging or bracing member T-shaped in cross-section and being angular in elevation and having its outer base portion welded integrally to the bent part of the section, the inner part of the wedging member being spaced apart from the section and designed to overlie

against the upper face of the outer part of the base of the rail, and a compound angular plate welded integrally to the upper end of the bracing or wedging member to receive and wedge against the under face of the outer part of the tread of the rail to support the same, and to wedge against the web of the rail.

2. Bracing means for a pair of rails consisting of two sections extending under the bases of both rails and having their inner adjacent ends adjustably connected and axially alined; the outer end portion of each section beyond where it passes under the base of a rail being bent upon itself, the bent portion being welded integrally to the upper face of the section, a wedging or bracing member T-shaped in cross-section and being angular in elevation and having its outer base portion welded integrally to the bent part of the section, the inner part of the wedging member being spaced apart from the section and designed to overlie against the upper face of the outer part of the base of the rail, a compound angular plate welded integrally to the upper end of the bracing or wedging member to receive and wedge against the under face of the outer part of the tread of the rail to support the same, and to wedge against the web of the rail, said bent portion of the outer end of the section terminating short of the outer edge of the base of the rail, to form a space into which the base of the rail is designed to wedge, said compound angular plate being additionally riveted to the upper part of the wedging member, the adjusting of the two sections axially toward each other causing the wedging member to more firmly wedge or brace between the base of the rail and the under face of the tread, to withstand the tendency of the rail leaning or bending outwardly, and means for locking said adjustable means for the sections.

In testimony whereof we have signed our names to this specification in the presence of two subscribing witnesses.

LEO A. MUNDWILLER.
HERBERT A. NOEDEL.
